UNITED STATES PATENT OFFICE

EMANUEL CORNELLA, OF CHICAGO, ILLINOIS

AEROPLANE

Application filed December 9, 1929. Serial No. 412,866.

This invention relates to aeroplane construction, the primary object of the invention being to provide an aeroplane designed for vertical as well as horizontal flight, to the end that the aeroplane may take off or be landed on an exceptionally small area.

Another object of the invention is to provide an aeroplane of the helicopter type eliminating the use of stationary wings or blades for supporting the aeroplane while in flight, and at the same time insuring the maintenance of a uniform equilibrium.

Another important object of the invention is the provision of an aeroplane having a plurality of sets of blades or planes so arranged that they may be moved in circular paths while revolving about their longitudinal axes causing the blades or planes to exert a vertical thrust on the downward movements of the blades or planes, and feather while the blades or planes move upwardly, reducing the resistance to the minimum.

A still further object of the invention is to provide means for regulating the pitch of the blades or planes to change the angle of flight of the aeroplane, insuring convenient and dependable control during flying as well as during the ascent and descent of the machine.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of an aeroplane constructed in accordance with the invention.

Figure 2 is an end elevational view thereof.

Figure 3 is an enlarged detail view illustrating one end of one of the cylinders, a portion of the cylinder being broken away.

Figure 4 is a longitudinal sectional view through one of the cylinders.

Figure 5 is a sectional view taken on line 5—5 of Figure 1.

Figure 6 is an enlarged detail view of the braking means used for holding the blades or planes against movement.

Referring to the drawings in detail, the fuselage of the machine is indicated generally by the reference character 5, and includes pairs of upper parallel bars 6 and lower parallel bars 7 connected at their ends by means of the vertical bars 8.

Disposed intermediate the ends of the bars 6 and 7, are pairs of vertical bars 9 that divide the machine into front and rear sections. Bearings 10 are secured to the bars 8 and 9, in which bearings shafts 11 are journaled, the shafts supporting the cylinders 12 that are arranged on opposite sides of the machine. On the inner ends of the shafts 11 are pinions 13, which pinions are in mesh with the worms 14, formed at the outer ends of the transverse shafts 15 that are mounted in the bearings 16 also secured to the vertical bars 9.

Mounted on the shafts 15 are pinions 17 that mesh with pinions 18 secured to the upper ends of the vertical shafts 19, there being provided pinions 20 on the lower ends of the shaft 19 that mesh with the pinions 21 operated by the internal combustion engines 22 associated therewith.

Thus it will be obvious that due to this construction, the cylinders 12 may be rotated in horizontal planes to operate the blades or planes to be hereinafter more fully described.

Secured within each cylinder 12, is a frame 23 that includes bars 24 connected at their ends, by the members 25 that are secured to the ends 26 of the cylinders 12. These bars 24 are formed with circular openings in which the inner ends of the shafts 27 are positioned,

the shafts being provided with pins 28 to permit of rotary movement of the shafts 27, but at the same time restrict lateral movement of the shafts. Extending through each shaft 27, is an arm 29, the arms 29 having their ends secured to the cables 30 that extend over the pulleys 31 mounted at the outer ends of the frames 23, the opposite ends of the cables moving over the pulleys 32 mounted at the opposite ends of the frames 23, the ends of the cables being connected to the operating disks 33 that are secured to the inner ends of the shafts 34 which are shown as extending through the inner ends of the cylinders 12. The shafts 34 operate through openings in the end members 26 and are supplied with coiled springs 35 that normally act to urge the disks 33 into close engagement with the brake shoes 36 that are secured to the brakes 37 mounted on the end members 26, to the end that the disks 33 are normally held against rotary movement. Mounted on each shaft 34 is an arm 38 which is secured to its shaft to rotate therewith. At the outer end of each shaft 34 is a head 39 designed to move over the shoes 40 that are secured to the vertical bars 9 at the ends of the machine, to the end that as the cylinders are rotated and the heads 39 move over the shoes 40, the shafts 34 will be forced inwardly, releasing the operating disks from the brake shoes and permitting the operating disks to be rotated.

These operating disks 33 are rotated by the action of the arms 38 which contact with the heads 42 and 43 respectively that are supported by the frame of the machine, and lie in the path of travel of the arms 38. With each rotation of the cylinders, the arms contacting with the heads 42 cause the disks to rotate to shift the shafts 27 to various angles to cause the blades or planes 44 mounted at the outer ends of the shafts 27 to move to various positions.

The movements of the arms 38 are timed so that when the blades or planes 44 are on the outside of the machine, the blades will be in horizontal positions, or slightly tilted from their horizontal positions, to exert an upward thrust on the machine, while the blades which are moving towards the inner portion of the machine will feather, so that the resistance is reduced to the minimum, and the blades or planes may pass each other without danger of contact.

The heads 43 are formed at the outer ends of the shanks 45 that are carried by the blocks 46 which move within the guides 47 mounted on the frame of the machine. Adjusting rods 48 connect with the blocks 46 and are provided with handles 49 whereby the adjusting rods may be moved to adjust the shanks 45 and heads carried thereby, so that the arms 38 may be caused to move the planes or blades 44 to various angles or pitches to con-

trol the movements of the machine. Thus it will be obvious that when the planes or blades 44 operate in horizontal positions, the machine will be directed upwardly in a vertical line, but when the blades are moved, so that the side faces thereof operate at oblique angles with respect to the sides of the machine, the blades will tend to move the machine forwardly and upwardly.

The reference character 50 designates the gas bag that supports the weight of the machine, and the reference character 51 indicates the rudder which is controlled in the usual and well known manner. The controls will extend to the compartment 52 in which the pilot is seated. The landing gear embodies wheels 53 that are mounted at the lower ends of the arms 54, as clearly shown by the drawings.

The operation of the device is as follows:

The engines are started and a suitable clutch mechanism not shown is thrown into operation to transmit rotary motion to the cylinders and planes or blades supported thereby. The planes or blades are adjusted so that on their downward movements they will be horizontal, directing an upward thrust to the machine, and causing the machine to ascend. When the desired elevation has been reached, the planes or blades are tilted to the proper angles to give a forward thrust to the machine, causing the machine to move along, the speed of the machine being controlled by the speed of the engines.

I claim:

1. In an aerial machine, a body portion, a gas bag for supporting the body portion, cylinders mounted on the body portion and adapted to rotate in horizontal planes, blades carried by the cylinders, means for rotating the blades to cause the blades to feather on their upward movements, braking means for normally holding the blades against movement, means for automatically releasing the braking means, and means for rotating the cylinders.

2. In an aerial machine, a body portion, a gas bag for supporting the body portion, cylinders mounted for rotary movement on the body portion, a plurality of blades extending laterally from the cylinders, operating disks supported within the cylinders, cables connecting the operating disks and blades to rotate the blades to cause them to feather on their upward movements, shafts on which the disks are mounted, arms secured to the shafts, means lying in the path of travel of the arms, for moving the arms to rotate the blades, and means for rotating the cylinders.

3. In an aerial machine, a body portion, a plurality of cylinders mounted for rotary movement on the body portion, shafts rotatably mounted and extending laterally from the cylinders, blades on the outer ends

of the shafts, operating disks supported within the ends of the cylinders, rods extending transversely through the shafts, cables connecting the rods and operating disks, shafts 5 on which the disks are mounted, arms secured to the shafts, an adjustable member having a head, lying in the path of travel of the arms, to move the arms and rotate the operating disks, to rotate the blade supporting 10 shafts, and means for rotating the cylinders.

In testimony that I claim the foregoing as my own, I have hereto affixed my signature.

EMANUEL CORNELLA.
